UNITED STATES PATENT OFFICE.

EDWIN W. GOESER, OF LOS ANGELES, AND WILLIAM C. McDUFFIE, OF HOLLYWOOD, CALIFORNIA, ASSIGNEES TO UNION TOOL COMPANY, OF TORRANCE, CALIFORNIA, A CORPORATION OF CALIFORNIA.

HIGH-SPEED ROTARY AND DRAW WORKS.

Application filed November 19, 1923. Serial No. 675,529.

To all whom it may concern:

Be it known that we, EDWIN W. GOESER and WILLIAM C. McDUFFIE, citizens of the United States, residing at Los Angeles and 5 Hollywood, Los Angeles, respectively, in the county of Los Angeles and State of California, have invented a new and useful High-Speed Rotary and Draw Works, of which the following is a specification.

10 This invention relates to rotary drilling apparatus for drilling oil and gas wells. Such apparatus usually includes a mechanism known as a rotary draw works which includes a rotary drum carrying a cable 15 which runs up to the crown block and thence downwardly to attach to the drill stem and support the same at a point above the rotary table. This drum enables the drill stem to be raised or lowered by power at will. On 20 occasions it would be advantageous if it were possible to give the drill a very slight movement up or down in the well, but it is, of course, impossible to do this with the power drive for the drum of the draw works. It 25 has been discovered that if a rotary drill bit is driven at a relatively high speed it is less apt to be twisted off than when driven at a relatively low speed. For this reason it is desirable to drive such a bit at a higher 30 speed than has heretofore been customary. However, this would necessitate running the engine at a higher speed than is practicable. Furthermore, the teeth of the gear carried 35 by the rotary table are usually made of cast iron and it would not be feasible to drive such a gear at this relatively high speed referred to above.

The general object of this invention is to 40 overcome these difficulties and to provide simple means to enable the drum to be rotated at will by hand instead of by power, and at a relatively low speed, to enable the driller to raise or lower the tool at the bottom of the well; also to provide simple 45 means for enabling the power to drive the rotary table and drill at a higher speed without increasing the speed of the engine, and to accomplish this without disturbing the regular alignment of the shafting that drives 50 the rotary table from the engine. One of the objects of the invention also is to provide a construction for the rotary table which

will enable it to be driven safely at a speed higher than any speed now employed for driving such a table. 55

Further objects of the invention will appear hereinafter.

The invention consists in the novel parts and combination of parts to be described hereinafter, all of which contribute to produce an efficient high speed rotary draw works. 60

A preferred embodiment of the invention is described in the following specification while the broad scope of the invention is 65 pointed out in the appended claims.

In the drawings:

Figure 1 is a side elevation partially broken away illustrating a rotary draw works and a rotary drill table with their 70 contiguous mechanism.

Fig. 2 is a vertical section upon an enlarged scale passing through one edge of the rotary drill table.

Fig. 3 is a plan and partial section illustrating the shafting for driving the drill table from the engine; this view particularly illustrates the step-up gearing for driving the rotary table at an increased speed ratio. 75

Fig. 4 is a vertical section taken about 80 on the line 4—4 of Figure 3.

Fig. 5 is a vertical section taken about on the line 5—5 of Figure 3.

Fig. 6 is a side elevation partially broken away and partially shown in section illustrating the mechanism at the end of the rotary draw works for enabling the drum to be rotated at will by hand. 85

Fig. 7 is a vertical section taken about in the plane of the line 7—7 of Figures 6 and 90 8, and particularly illustrating details of a worm and wheel through which the hand force is applied to rotate the drum.

Fig. 8 is a plan and partial section taken about on the line 8—8 of Figure 6 and particularly illustrating details of the clutch means which enables a hand operated member to be connected to the drum at will. 95

Fig. 9 is a section taken on the line 9—9 of Figure 8 upon an enlarged scale, and 100 particularly illustrating details of the hand power clutch means.

The drilling apparatus includes a rotary table 1 which is rotatably mounted on the

floor 2 of a derrick. On one side of this derrick a rotary draw works mechanism 3 is provided including a rotary drum 4 mounted on a drum shaft 5. The drum is rigid on the drum shaft and the drum shaft may be rotated by power from a line shaft 6 through a sprocket chain 7 connecting sprocket wheels 8 and 9 alining with each other, see Figure 6.

10 We provide means for disconnecting the power drive to the drum at will and this means may consist of a clutch 10 having a relatively fixed clutch member 11 which may be formed as a hub of the sprocket wheel 9 and including a relatively movable clutch member 12 which is mounted to slide on the shaft 5, being driven continuously by a spline 13. This clutch may be opened or closed at will by means of a usual clutch 20 lever 14.

We provide hand actuated mechanism for rotating the drum 4 at will when the power clutch 10 is open. For this purpose we prefer to extend the shaft 5 beyond its bearing 25 15, see Figure 6, and on the extension of the shaft we provide a loose worm wheel 16, associated with which we provide a hand-power clutch 17 including a relatively fixed clutch member 18 formed as a hub on the 30 worm wheel and a sliding clutch member 19 splined on the shaft and operatable at will by a treadle controlled clutch lever 20. The hand actuated mechanism further includes a worm 21 meshing with the worm wheel and 35 this worm may be driven by a hand operated member such as a hand wheel 22, see Figure 7. If desired the hand wheel 22 may be attached directly to the shaft 23 of the worm but we prefer to provide two speeds

40 for driving the drum shaft by hand, that is to say, we prefer to provide a relatively slow hand driving gear train for rotating the drum in a direction to raise the tool slowly, and a second gear train which may be connected up to enable the tool to be lowered in the well at a somewhat higher speed than it is raised. In order to accomplish this we provide hand clutch means 24, see Figures 45 8 and 9, and we provide two gear trains,

50 either of which may be connected operatively to the worm wheel 16. We shall first describe the relatively low speed gear train which is used for raising the drill by hand. This gear train includes a pinion 25 formed

55 on a hollow spindle 26 adjacent to which the hand wheel 22 is loosely mounted. This pinion 25 meshes with a gear wheel 27 loosely mounted on a fixed stud 28 and having a tubular shaft formed into a pinion 29

60 which meshes with a gear wheel 30 rigidly secured to the shaft 23 of the worm. The hand wheel 22 is keyed to a tubular inner shaft 31 disposed within the shaft 31. Between the tubular shaft 31 and the outer tubular shaft 26 we provide a special clutch

corresponding to this gear train, and this special clutch comprises a drum or clutch wheel 32 which is rigid on the outer shaft 26. Rigid on the inner shaft 31 we provide a clutch wheel 33 which is of considerably 70 smaller diameter than the inner diameter of the wheel or drum 32, see Figure 9. In the space between the outer face of the wheel 33 and the inner face of the rim of the drum 32, we provide an expansion ring 34 which is split at one point to receive an expansion head 35 which is of wedge form so that its side faces come against inclined faces 36 formed at the ends of the expansion ring. The expansion head 35 is carried on the end of an expansion pin 37 and this pin can be shoved outwardly at will by means of a hand controlled sliding pin or key 38, see Figure 8. This pin 38 slides freely in the bore of the inner tubular shaft 31 and has an inclined 80 face 39 on its side which engages the inner end of the clutch pin 37. By shoving this pin in, the face 39, which is of cam form, will operate to shove the pin 37 outwardly and this produces an expansion of the expansion ring through the operation of the expansion 90 head 35.

The clutch means 24 includes another special clutch 40 which is similar in construction to the clutch already described, 95 but this clutch is associated with a gear wheel 41 carried on a short sleeve 42 which is similar to the shaft 26. In other words the rim of this gear wheel 41 performs the function of the drum 32 of the other clutch. It is also provided with teeth which mesh with the pinion 29 already described. In this way, if the pin or key 38 is put in a proper position, a wedge head 43 corresponding to this clutch 40 will close this clutch at the same time opening the clutch at 32. In other words to close the clutch 40 the pin 38 should be pulled out so that the cam formed on the inner end of the pin 38 shoves the expansion head 43 out; when the pin 38 is in this position the cam face 39 will release the pin 37 so that the other clutch will be open.

Referring to Figure 1, the cable is indicated by the dotted line 44, running up to 115 the crown block and hanging down at the point indicated by the line 45 on the axis of the well so as to be secured to the upper end of a drill string which passes down through the rotary table 1.

The engine which furnishes the power for driving the rotary drum and the rotary table is located over to the left as viewed in Figure 1, and the engine drives the sprocket chain 46 which drives the aforesaid counter shaft 6.

Shafting is provided for driving the rotary table 1 from the engine and this shafting is usually driven through a beveled gear 47, see Figure 1, carried by a driving shaft 130

48 which passes under the drum 4 and is in alignment with the center of the rotary table. Between the rotary table and the rotary draw works, we provide step-up speed 5 mechanism so that the shaft 48 will drive the rotary table at an increased speed ratio. The rotary table is provided with a bevel gear or gear ring 49, the teeth of which mesh with a pinion 50 carried on a driven shaft 10 51, which is in alignment with the driving shaft 48 and extends toward the center of the table, see Figure 3. At the adjacent ends of the shafts 48 and 51, which substantially abut against each other, we provide 15 step up gearing so that the driven shaft 51 will be driven at a higher speed than the shaft 48. For this purpose we provide a counter shaft 52 carrying a pinion 53 which is driven by a gear wheel 54 on the 20 driving shaft 48. This pinion 53 is rigid on the shaft 52 and through a gear wheel 55 on the counter shaft 52 drives a pinion 56 carried on the driven shaft 51. All of the shafting may be mounted in suitable 25 roller bearings, and the bearings and gears may all be enclosed in a suitable gear case 57 including a removable cover 58, see Figure 5.

The rotary drill table rotates on hardened 30 steel balls 59, see Figure 3, which run in a suitable ball race. For a high speed such as used for driving this rotary table, we prefer balls to rollers.

The high speed employed for driving the 35 beveled gear or gear ring 49 makes it impossible to use the usual beveled gear made of a casting and having separate teeth secured to the body of the ring. In order to overcome this objection we provide a construction for the table, such as that illustrated in Figure 2, in which the gear ring 49 is formed of a forging or of cast steel. This ring and the body 60 of the 40 rotary table are constructed in such a way as to permit the ring to be shrunk onto the body. In order to accomplish this and provide for resisting upward thrust which may be imparted to the ring by the teeth of the driving pinion 50, we provide the body 50 60 of the rotary table with a substantially cylindrical face 61 below which we provide a relatively wide shoulder 62 which operates as a seat for the ring 49. Near the upper face 63 of the table, we provide a relatively 55 narrow annular shoulder 64, see Figure 2. By heating the ring 49 to a high temperature its inner diameter will increase sufficiently to enable it to pass over the shoulder 64. The ring will then be shoved down onto its seat 62 and when it cools a shoulder upon it corresponding to the shoulder 64 will engage with the shoulder 64 and prevent any possibility of the ring 49 being displaced upwardly on the body of the rotary table. The 60 teeth 65 of the ring 49 are made integral

with the ring and are cut in the ring by gear cutters or hobbing tools.

We shall now briefly describe the general mode of operation of the mechanism. Through the chain 46 the engine drives the 70 line shaft 6 and this motion is imparted to the rotary drum shaft 5 through the sprocket chain 7 and sprocket wheels 8 and 9, see Figure 6.

When it is desired to raise or lower the 75 drilling tool in the well, the driller opens the clutch 10 by means of the clutch lever 14, and by means of the clutch lever 20 he closes the clutch 17, which is normally held open by its spring 20^a. If it is desired to raise the tool in the well, the slow moving gear train should be connected to the hand wheel 22, and this is accomplished by pushing in the clutch pin 38. This closes the clutch at 32, and rotation of the hand wheel 80 will then be imparted through the pinion 25 to the gear 27, and through the pinion 29 to the gear wheel 30 on the worm 21. The rotation of the worm will rotate the worm wheel 16, and the rotation of this worm 85 wheel will be imparted through the clutch member 19 to the drum shaft 5, to take up the cable.

If the pin 38 is pulled out instead of being shoved in, as described, the clutch at 40 will 90 be closed so that the gear wheel 41 will rotate the pinion 29 which operates as an idler to drive the gear wheel 30, operating to drive the worm 21 at a relatively higher speed, in a direction to pay out the cable.

The engine drives the shaft 48 which extends under the drum 3, and through the gears 54, 53, 55 and 56 the driven shaft 51 is driven at a higher speed ratio, thereby enabling the pinion 50 to drive the rotary table at a higher speed than would be possible if it were driven directly from the engine.

The fact that the driving shaft 48 is in alignment with the driven shaft 51, with both of these shafts on a line passing through the center of the rotary table, it is evident that no change is necessary for this drive, in the general alignment of the shafting, but it is merely necessary to provide the 100 counter shaft 52 with its step-up gear train. This feature enables a straight drive shaft arrangement to be readily transformed into this stepped up speed drive without making 105 general alterations in the mechanism.

The body 60 of the rotary table is provided with a projecting annular lip or apron 60^a (see Fig. 2) which covers the outer side of the ball-race and keeps mud out of it.

The customary locks and pawls may be provided on the drive shaft and the regular universal coupling may be provided for the drive shaft.

It is understood that the embodiment of 110 the invention described herein is only one of

the many embodiments this invention may take and we do not wish to be limited in the practice of our invention nor in our claims to the particular embodiment set forth.

5. What we claim is:

1. In rotary well drilling apparatus, the combination of a rotary drilling table, a cable drum for carrying a cable to support the drilling tool in the well, power actuated means for driving the drum, means for disconnecting the power-drive to the drum at will, two-speed hand actuated mechanism, and means for connecting the same at will to the drum for rotating the drum by hand at either speed.
2. In rotary well drilling apparatus, the combination of a rotary drilling table, means for driving the rotary table, a cable drum for carrying a cable to support a tool in the well, means for driving the drum including a clutch, a two-speed hand-driving mechanism for rotating the drum, means for opening the clutch to permit the drum to be rotated by hand, and means for connecting the hand-driving mechanism to rotate the drum by hand at either speed.
3. In rotary well drilling apparatus, the combination of a rotary drilling table, means for driving the rotary table, a cable drum for carrying a cable to support a tool in the well, means for driving the drum including a clutch, a lever for opening the clutch to permit the drum to be rotated by hand, hand-driving mechanism, and a clutch with a lever independent of the first named lever to connect the hand-driving mechanism to the drum at will for rotating the same by hand.
4. In rotary well drilling apparatus, the combination of a rotary drilling table, means for driving the rotary table, a cable drum for carrying a cable to support a tool in the well, means for driving the drum including a clutch, a hand-driving mechanism for rotating the drum by hand and including means for driving the drum at a relatively low speed for raising the tool, and means for rotating the drum at a relatively higher speed for lowering the tool, means for opening the clutch to permit the drum to be rotated by hand, and means for connecting the hand driving mechanism at will to the drum shaft for rotating the drum by hand.
5. In rotary well drilling apparatus, the combination of a rotary drilling table, means for driving the rotary table, a cable drum for carrying a cable to support a tool in the well, means for driving the drum including a clutch, means for opening the said clutch to permit the drum to be rotated by hand, hand driving mechanism including a gear train for rotating the drum at a relatively low speed in a direction to take up the cable and raise the drilling tool, and

also including another gear train for rotating the drum at a relatively higher speed in a direction to pay out the cable and permit the drilling tool to descend, and means for connecting the hand-driving mechanism at will to the drum shaft for rotating the drum by hand.

6. In a rotary well drilling apparatus, the combination of a rotary draw works mechanism including a cable drum for carrying a cable to support the drilling tool in the well, power driving means including a clutch for driving the drum, means for opening the clutch at will, a hand actuated member, a gear train capable of being driven by the hand actuated member and connected with the drum to rotate the same at a low speed in a direction to raise the tool, another gear train capable of being driven by the hand actuated member for rotating the drum at a relatively higher speed in a direction to lower the tool, clutch means having a controlling member operating in one position to connect the hand actuated member to the drum through one of said gear trains and having another operative position for connecting the other gear train with the drum whereby the tool may be raised or lowered by hand at will when the power clutch is open.

7. In a rotary well drilling apparatus, the combination of a rotary draw works mechanism, including a cable drum for carrying a cable to support the drilling tool in the well, power driving means including a clutch for driving the drum, means for opening the clutch at will, hand-actuated mechanism for rotating the draw works drum at a low speed to raise or lower the tool at will, with means for connecting the same to the drum at will, shafting extending past the rotary draw-works mechanism for driving the rotary table by power, and step-up mechanism associated with the shafting and located between the rotary draw works mechanism and the table.

8. In a rotary well drilling apparatus, the combination of a rotary draw works mechanism including a cable drum for carrying a cable to support the drilling tool in the well, power driving means including a clutch for driving the drum, means for opening the clutch at will, hand-actuated mechanism for rotating the draw works drum at a low speed to raise or lower the tool at will, with means for connecting the same to the drum at will, a driving shaft extending under the drum and axially aligned with the center of the rotary table, a driven shaft aligned with the driving shaft extending toward the table and having means for rotating the rotary table, a counter-shaft parallel to the driving shaft and driven shaft and located opposite the adjacent ends of the driven shaft and driving shaft, and

step up gearing between the counter shaft and the other shafts for driving the table at an increased speed ratio.

9. In a rotary well drilling apparatus, the combination of a rotary draw works mechanism including a cable drum for carrying a cable to support the drilling tool in the well, power driving means including a clutch for driving the drum, means for opening the clutch at will, hand actuated mechanism with a gear train for rotating the drum at a relatively low speed to rotate the same slowly in a direction to raise the drill tool, and including a second gear train for rotating the drum at a relatively higher speed in a direction to lower the tool in the well, a rotary table, a driving shaft extending under the drum with step-up gearing located between the drum and the table for rotating the table at an increased speed ratio.

10. In a rotary drilling apparatus, the

combination of a rotary draw works mechanism including a cable drum for carrying a cable to support the drilling tool in the well, power driving means including a 25 clutch for driving the drum, means for opening the clutch at will, hand actuated mechanism for rotating the drum, a clutch for connecting the same at will to the drum for rotating the drum slowly by hand at 30 will to raise or lower the tool, a rotary table, shafting for driving the rotary table extending from a point near the drum and having a pinion adjacent the rotary table for driving the same, said table having a 35 body with a gear ring carrying teeth shrunk onto the body, and step-up gearing associated with the shafting for driving the rotary table at an increased speed ratio.
